(57) **CLAIM**

The ornamental design for a puzzle, as shown and described.

DESCRIPTION

FIG. 1 shows an upper left perspective view of a puzzle in a first configuration according to the new design.

FIG. 2 shows a front elevation view thereof.

FIG. 3 shows a rear elevation view thereof.

FIG. 4 shows a top plan view thereof.

FIG. 5 shows a bottom plan view thereof.

FIG. 6 shows a left elevation view thereof.

FIG. 7 shows a right elevation view thereof.

FIG. 8 shows an upper left perspective view of the puzzle of FIG. 1 in a second configuration.

FIG. 9 shows a front elevation view thereof.

FIG. 10 shows a rear elevation view thereof.

FIG. 11 shows a top plan view thereof.

FIG. 12 shows a bottom plan view thereof.

FIG. 13 shows a left elevation view thereof.

FIG. 14 shows a right elevation view thereof.

FIG. 15 shows an upper right perspective view of the puzzle of FIG. 1 in a third configuration.

FIG. 16 shows a front elevation view thereof.

FIG. 17 shows a rear elevation view thereof.

FIG. 18 shows a top plan view thereof.

FIG. 19 shows a bottom plan view thereof.

FIG. 20 shows a left elevation view thereof.

FIG. 21 shows a right elevation view thereof.

FIG. 22 shows an upper right perspective view of the puzzle of FIG. 1 in a fourth configuration.

FIG. 23 shows a front elevation view thereof.

FIG. 24 shows a rear elevation view thereof.

FIG. 25 shows a top plan view thereof.

FIG. 26 shows a bottom plan view thereof.

FIG. 27 shows a left elevation view thereof; and,

FIG. 28 shows a right elevation view thereof.

Surface shading forms no part of the claimed design.

1 Claim, 21 Drawing Sheets
